UNITED STATES PATENT OFFICE.

WILLIAM H. JONES, OF HUDSON, COLORADO.

RAILWAY-TIE.

1,016,414.

Specification of Letters Patent.

Patented Feb. 6, 1912.

Application filed April 21, 1911. Serial No. 622,515.

To all whom it may concern:

Be it known that I, WILLIAM H. JONES, a citizen of the United States, residing at Hudson, in the county of Weld and State 5 of Colorado, have invented certain new and useful Improvements in Railway-Ties, of which the following is a specification.

This invention relates to railway ties of that class which are constructed of concrete 10 or other plastic material or composition, and it is the object of the invention to provide a strong and durable tie of this kind, and also novel and improved rail fastening means whereby the rails will be securely 15 held in place without the use of spikes.

The invention also has for its object to provide a fastening which enables track 20 repairs to be readily made, the fastening being so arranged that the rails can be easily removed.

Other objects and advantages of the invention will be manifest when the same is better understood, reference being had to the accompanying drawing forming a part 25 of this specification, in which drawing—

Figure 1 is a plan view of the tie and the rail fastening. Fig. 2 is a cross section on the line 2—2 of Fig. 1. Fig. 3 is a longitudinal section on the line 3—3 of Fig. 1.

Referring specifically to the drawing, 5 denotes the body of the tie, the same being constructed of concrete or any other plastic material, such as wood-pulp paper, straw-board, etc. The tie is reinforced by embedding metal rods 6 therein, each of said rods running lengthwise from one end of the tie to the other, and being arched up under the rail seats at the ends of the tie. Two sets of rods are employed, said sets 25 being spaced apart vertically a suitable distance, and each set comprising four rods arranged in a transverse row. The rods of the upper row are connected to the corresponding rods of the lower row by tie 40 wires 7.

On the bottom of the tie, at each end thereof, is a metal plate 8 which protects the tie when tamping, and also serves to hold the heads of the bolts which secure the rail 50 fasteners to be presently described. Each end of the tie is provided with a rail fastener, and as they are alike in structure, a description of one suffices for both.

The rail fastener comprises a metal plate 55 9 which is placed on the top of the tie, and is fastened thereto by two bolts 10 passing

through the plate adjacent to the ends thereof, and through the top of the tie, as well as through the plate 8, the head of the bolt engaging the bottom of the latter. The 60 bolts are secured by nuts 11 screwed on the ends thereof against the top of the plate 9. The outer end of the plate 9 is bent over and doubled as indicated at 12 through which portion one of the bolts 10 passes. 65 The bent over portion of the plate terminates in an upward bend 13 to form a clip under which one of the base flanges of the rail 14 extends, said clip extending at such an angle as to fit on said base flange. The 70 other base flange of the rail 14 is engaged by a clip 15 formed by bending up one end of a metal strip 16 carried by the plate 9. This strip has, adjacent to its end which is formed with the clip 15, a downward 75 bend to form a groove 17 which receives a transverse key 18. This downwardly bent portion of the strip seats in an opening 19 made in the plate 9, and extends below the plane of the bottom of said plate a sufficient 80 distance to bring the groove below said plate so that the key may be placed under the plate, and passed through the groove. The key extends across the plate from one side thereof to the other, and thus forms a rigid 85 fastening for the strip 16. The top of the tie 5 has a transverse groove 20 to receive the grooved portion of the strip.

The key 18 is tapered in the direction of one of its ends so that when it is driven 90 home it will be tightly wedged in place, and the small end of the key also has a hole to receive a split key or cotter 21 which engages one edge of the plate 9.

By the herein described structure the rail 95 will be securely held in place on the tie, and at the same time it can be readily removed, it being necessary only to remove the key 18, after which the strip 16 can be taken off, whereupon the rail is released 100 on one side, and can be removed by being slipped from under the clip 15 on the other side thereof.

I claim:

The combination with a railway tie having a top transverse groove, of a rail fastening comprising a plate extending transversely beneath the rail to form a seat therefor, and projecting from opposite sides thereof, said plate being bent over at one of its ends to form an integral rail-holding clip adapted to engage the corresponding 110

side of the rail, and said plate on the other side of the rail being provided with an opening which registers with the aforesaid groove; a rail-holding clip engageable with 5 the other side of the rail, said last-mentioned clip seating on the plate and having a downward bend through the aforesaid opening and beneath the plane of the bottom of the plate into the transverse groove; 10 a key passing transversely under the plate on opposite sides of the groove, and across

the top of the bent portion of the clip; and fastening devices passing through the ends of the plate into the tie, one of said fastening devices passing through the bent- 15 over portion of the plate.

In testimony whereof I affix my signature in presence of two witnesses.

WILLIAM H. JONES.
